UNITED STATES PATENT OFFICE.

DUGALD H. ROBERTS, OF DETROIT, MICHIGAN.

DESIGN FOR A LUBRICATOR-BODY.

SPECIFICATION forming part of Design No. 28,653, dated May 17, 1898.

Application filed July 6, 1897. Serial No. 643,660. Term of patent 14 years.

To all whom it may concern:

Be it known that I, DUGALD H. ROBERTS, a citizen of the United States, residing at Detroit, in the county of Wayne, State of Michigan, have invented and produced a new and original Design for the Body of a Lubricator, of which the following is a specification, reference being had to the accompanying drawings, and to the letters of reference marked thereon, which form a part of this specification.

This invention relates to a new and original design for the body of a lubricator; and it consists in the formation and contour illustrated in the accompanying drawings, in which—

Figure 1 is an elevation of my design. Fig. 2 is a transverse section therethrough on line 2 2 of Fig 1.

The leading feature of my design consists in the general shape and configuration of a

lubricator-body, as shown in the accompanying illustrations.

The body A of the lubricator describes an oblong cylinder, provided at its lower end 25 with a transverse member B, at the opposite ends of which are the right-angled members C and D, respectively. Depending from said cross-arm is a member F. Projecting from the cylindrical face of the body A is a cross E, 30 while upon the top of said body is a rounded molding H.

Having thus fully set forth my invention, what is claimed is—

The design for a lubricator-body substantially as herein shown and described. 35

In testimony whereof I affix my signature in presence of two witnesses.

DUGALD H. ROBERTS.

Witnesses:

E. S. WHEELER,
M. A. MARTIN.
